UNITED STATES PATENT OFFICE.

WILLIAM A. EATON, OF GRAND RAPIDS, MICHIGAN.

SPRAYER.

1,176,042.

Specification of Letters Patent. Patented Mar. 21, 1916.

Application filed September 18, 1914. Serial No. 862,377.

To all whom it may concern:

Be it known that I, WILLIAM A. EATON, a citizen of the United States, residing at Grand Rapids, in the county of Kent and 5 State of Michigan, have invented new and useful Improvements in Sprayers, of which the following is a specification.

The invention relates to a sprayer, and more particularly to a device simulative of a 10 double acting pump comprising juxta-positioned barrels, pistons arranged to operate within such barrels, and an intermediate tube having communication with one of the barrels, and means for spreading the jets 15 at their delivery.

The invention consists of a double-acting pump embodying parallel barrels, connected pistons, a tank, and a tube having connection with one of the barrels, the parts being 20 of such construction and arrangement as to assure a continuous discharge when the device is in operation.

The invention consists of the novel features, details of construction, and combination 25 of parts which will be hereinafter more fully set forth, illustrated and claimed.

In the accompanying drawing:—Figure 1 is a perspective view of a double acting pump embodying the invention. Fig. 2 is a 30 longitudinal sectional view thereof. Fig. 3 is a sectional view on the line 3—3 of Fig. 2.

Similar reference characters indicate corresponding parts throughout the several views in the drawing.

35 Referring to the drawing in detail, the device comprises barrels 1 and 2 which have a parallel arrangement and are disposed in close relation. Pistons 3 and 4 are arranged to operate in the respective barrels, and 40 their rods are connected to a cross piece 5 which constitutes a handle whereby both pistons are simultaneously operated, the one drawing a charge into one barrel, whereas the other expels the charge previously drawn 45 into the opposite barrel. One of the rods is adapted to move in a stuffing box 6 which is carried by the cylinder 2.

Disposed above the barrels 1 and 2 and fixed thereto in any suitable manner inter- 50 mediate the same is a tube 7 which has communication with the barrel 2, the inner end of the tube being closed, while the outer end

is formed with an aperture 8 to permit the discharge of the contents from the said barrel on movement of the piston therein in 55 one direction.

A tank 9 is located beneath the barrels 1 and 2, and is connected thereto in any suitable manner, one end of the tank being extended a distance beyond the ends of the 60 barrels, and rising from the extended end of the said tank are two jet tubes 10 and 11, respectively, the tube 10 being designed to terminate next to an opening 12 in the barrel 1, while the tube 11 terminates next to 65 the aperture in the tube 8 so that contents from the tank 9 can issue from the tubes across the path of the apertures in the respective barrel and tube for the distribution 70 of such contents.

In the operation of the device the pistons move simultaneously in the same direction, one of the pistons drawing a charge into 75 one of the barrels, and the other piston at the same time expelling the charge previously drawn into the other barrel. The pistons have an alternate action with the result that a continuous discharge is produced.

From the foregoing description, taken in connection with the accompanying drawing, 80 it is thought that the construction and manner of operation of the device will be clearly understood.

What is claimed is:—

In a device of the character described, in 85 combination a pair of barrels, a tank upon which said barrels are mounted, said tank projecting in advance of said barrels, a liquid discharge tube projecting radially from said barrel and communicating therewith, a 90 longitudinally disposed tube integrally formed upon one of said barrels and having its axis disposed between said barrels, the outer end of said tubes being adjacent each other and ported, a second liquid discharge 95 tube alongside the first named tube and co-extensive therewith disposed opposite one of said barrels, the said barrel having a discharge port directly adjacent the outlet of said second liquid discharge tube, a separate 100 piston operating in each barrel, a pair of piston rods passing through said barrels and secured to said pistons, a handle connecting said rods exteriorly of said barrels, the bar-

rel having said port being formed at its end opposite to said port with an air inlet opening, the opposite barrel being formed at its end adjacent said liquid discharge tubes
5 with an air inlet and communicating at its opposite end with said longitudinally disposed tube.

In testimony whereof I affix my signature in presence of two witnesses.

WILLIAM A. EATON.
